UNITED STATES PATENT OFFICE.

RAYMOND C. PENFIELD, OF NEW YORK, N. Y.

PORTABLE BRICK-HANDLING DEVICE.

967,663.

Specification of Letters Patent. Patented Aug. 16, 1910.

Application filed October 24, 1908. Serial No. 459,348.

To all whom it may concern:

Be it known that I, RAYMOND C. PENFIELD, a citizen of the United States of America, residing at New York city, in the 5 county of New York and State of New York, have invented certain new and useful Improvements in Portable Brick-Handling Devices, of which the following is a specification, reference being had therein to the 10 accompanying drawing.

My present invention refers to a portable device for transporting bricks and other masses of material in bulk consisting of independent detached regular blocks from one 15 place to another.

The object is to provide simple and efficient locomotive mechanism provided with gripping means for laying hold of a mass of brick which has been set with its individual 20 members in a pre-arranged order and lifting the same from the ground or floor on which it is set so as to carry it to a kiln or to a place of storage or elsewhere as may be desired.

25 The invention consists essentially in transporting and lifting mechanism combined and arranged to produce the result in view, and in various details and peculiarities in the construction and combination, substantially 30 as will be hereinafter described and claimed.

In the accompanying drawings, illustrating 35 my invention, Figure 1 is a rear elevation of my improved portable device for transporting bricks and other masses of material. Fig. 2 is a sectional side elevation of the same. Fig. 3 is a top plan view. Fig. 4 is an enlarged cross sectional detail of one 40 of the clamping devices. Fig. 5 is a sectional side elevation of a modified form of the invention. Fig. 6 is an enlarged detail view of the eccentric device belonging to the latter form.

Similar characters of reference designate 45 corresponding parts throughout the different figures of the drawing.

The truck or portable device to which this invention relates is intended for use with a stack formation of bricks, which stack formation is built with the members of the 50 basic layer spaced apart at uniform or substantially uniform distances, so that lifting means may be inserted between the members of the basic layer for the purpose of raising the mass and gripping the members of the 55 basic layer at the same time so as to enable the latter to be raised with the upper mass.

In Figs. 2 and 5 I have shown at A a stack of bricks hacked up in the manner stated with the members of the basic layer spaced apart.

60 The truck or portable device is preferably of the hand variety, and a part of the general framework thereof is of the kind commonly employed in handling goods of various kinds in warehouses, freight sheds, and other places of shipment. Said frame may consist of the side bars 1, 1, having the handles 1^a. These side bars 1, 1 are connected by transverse pieces 2, and in one end of said side bars is supported the axle or shaft 65 3 provided with wheels 4, 4 which are situated at points outside of the main frame, as indicated in Figs. 1 and 3. At the lower end of the said truck frame is an elongated horizontal base bar 5 preferably cast integral with said truck frame, or securely attached thereto by suitable means such as bolts. This bar 5 is provided with a series 70 of vertical slots 6 (see Figs. 1, 2 and 5) through which operate wedge bars 7 that act 75 to spread apart the members of the pairs of clamps that grip the basic layer of bricks in the manner to be presently explained. Securely fastened to the base bar 5 are vertical side bars 8 that are connected together 80 at their upper ends by means of a horizontal transverse bar 9 to form a main skeleton framework which lies alongside the unit stack A in the manner shown in Figs. 2 and 6, said skeleton framework being secured to 85 and made a part of the truck frame by means of the upper angular braces 10 and the intermediate braces 11. This general framework may vary within wide limits, and I do not wish to be restricted thereto. I give 90 the present combination simply as a specimen illustration of how it may be made to 95 perform practical service.

100 Integral with or securely fastened to the base bar 5 is a series of lifting arms or members 12, consisting of rectangular frames having an upper bar 13 and a bottom bar or foot 14. Pairs of side clamping plates 15, 15 are hinged by means of hinges 17 to the top bar 13. These clamping plates are arranged 105 to move horizontally. The detailed construction of the lifting and clamping devices is shown in Fig. 4. These lifting arms 12 are secured or made integral with the horizontal bar 5 at points opposite the vertical slots 6, 110 so that the wedging bars 7 which pass through the slot 6 may enter between the

clamping plates just above the foot part 14, as seen in Figs. 2 and 4, and be in a position to act in conjunction with wedges on the hinged side plates 15. The top bars 13 are calculated to rest beneath the second layer of bricks and by lifting thereon, as shown in Figs. 2 and 6, to raise the superposed mass. Further, these lifting members pass between the individual units of the basic layer, being 10 of proper size to be inserted in the uniform spaces between these members of the basic layer, while the side plates 15 are adapted to be spread laterally for the purpose of gripping or clamping the members of the basic 15 layer by a pinching strain, so that when the superposed mass is lifted by the power exerted thereon by the lifting members 12, the simultaneous pinching strain on the bricks of the lower layer caused by the lateral action 20 of the plates 15 will lift the basic row also. On the inside face of each of the side plates 15, I place a number of wedges 16, preferably three, those on the one plate being inclined oppositely to those on the companion plate, and being placed so that they will interlock as shown in Figs. 2, 4 and 6. The upper portion of the wedge bars 7 are wedge-shaped, having inclined faces, and hence it is obvious that as said bars lift their upper 25 edges will come into contact with the inclined faces of the wedges 16, and the result will be that the plates 15 will be spread apart, swinging on their hinges 17. These plates 15 are preferably thin pieces of sheet 30 metal, and are adapted to spread easily and clamp tightly against the adjacent faces of the bricks. As the wedge bar 7 drops back, the wedge-provided plates 15 likewise drop back into their normal position, which is a 35 vertical one, with the two plates belonging to each lifting member parallel to each other, as shown in Fig. 4.

The wedge bars 7 which constitute the means for spreading apart the two clamping 45 plates belonging to each lifting member are formed with right-angled integral rods 18 that are provided with spiral springs 19 surrounding them. The rods 18 are screw-threaded and furnished with nuts 20 against 50 which one end of each of the spiral springs 19 bears. These rods 18 are mounted in the flanges 21 and 22 of a channel bar 38. A vertically-movable frame consists of the channel bar 38, a head plate 23, the parallel vertical center bars 24 secured to said head 23 and also to the flange 21 of the channel bar 38, and the inclined braces 25 which are bolted to the head piece 23, and also the flange 21 near the outer ends of the latter. Bolts 26 55 are employed to pass through the ends of the braces 25, the parallel bars 24 and the head 23. The head 23 carries a depending screw 27 on which is a worm wheel 28 which is engaged by a worm 29 having thereon a hand 60 wheel 30. The worm shaft 29 is supported 65

in suitable bearings 31 in the main frame near the stack of bricks, and also in the frame near the truck handles 1 as shown in Fig. 2. By rotating the hand wheel 30, the worm wheel 28 is revolved and the screw 27 fed up or down. When it is fed upwardly it is obvious that the entire movable frame will be lifted, which will compress the springs 19 and yieldingly raise the stems 18 and the wedges 7 carried by said stems, the result of 70 which movement will be to spread apart the members of the clamping devices. The interposition of the series of springs 19, however, enables the clamping devices to be spread with an elastic effect, which will permit variations in the thickness of the bricks to be compensated for as well as variations in the width of the spaces between the bricks of the basic layer. 75

Instead of the worm gear and hand wheel 80 operating mechanism for the vertically movable frame and the series of clamping devices, as shown in Figs. 1 and 2, I may employ different means for actuating the clamps, and one other specimen of means 85 which may be used for this purpose is illustrated in Figs. 5 and 6 where it is seen to consist essentially of an eccentric 32 carried fast on a shaft 33 which is supported in rigid bearings 34, 34 in the main frame. 90 The eccentric 32 works in a slot 35 in the cross piece 36 which forms a part of the vertically movable frame which carries the clamping wedges 7. On the end of the shaft 33 is a lever 37 whereby the shaft 33 is 95 rocked back and forth for the purpose of partially rotating the eccentric 32 in one direction or the other, and thus lifting or lowering the movable frame, thereby clamping or releasing the devices which grip the 100 bricks. Still other forms of actuating mechanism for the movable frame and the clamping wedges may be employed, and I reserve the liberty of employing any suitable mechanism for operating said wedges and clamps. 105

Many changes in the precise construction, arrangement and combination of the various parts may be made without exceeding the scope of the invention, provided only the legitimate lines of the appended claims are 110 adhered to in such modifications as may be employed in practice.

Having thus described my invention, what I claim as new and desire to secure by Letters Patent, is:

1. A portable device for carrying bricks and the like, comprising a locomotive frame, wheels therefor, and a series of lifting arms each provided with a pair of clamping plates hinged to opposite sides of the arm, said arms and their clamping plates being adapted to be inserted in the spaces between bricks which have been set in a pre-arranged order. 120

2. A portable device for transporting 125

bricks and the like, comprising a main frame, wheels or trucks therefor, a series of laterally projecting arms on the main frame which are adapted to be inserted between 5 adjacent bricks of a layer, and a pair of clamps arranged in connection with each of said arms for gripping the bricks simultaneously with the lifting of the entire mass, together with manually-operated means for 10 actuating the clamping members.

3. A portable device for transporting bricks and the like, comprising a main frame having a truck construction combined therewith, a series of lifting arms on the 15 lower end of the main frame adapted to be inserted between adjacent bricks of a layer, pairs of clamping members arranged in connection with the lifting arms, and a vertically movable frame provided with manu- 20 ally operated means for actuating the clamping members.

4. A portable device for carrying bricks, comprising a main frame having a truck construction combined therewith, a series of 25 lifting arms carried at the lower end of the main frame and adapted to be inserted between adjacent bricks of a layer, pairs of clamping members arranged in connection with said arms, vertically movable wedge 30 bars for actuating said clamping members, and means for simultaneously operating said wedge bars.

5. A portable device for carrying bricks, comprising a main frame having locomotive 35 mechanism combined therewith, a series of lifting arms carried at the lower end of said main frame, pairs of clamping plates whose members are movably connected to the lifting arms and are adapted to be 40 spread laterally, wedges on the inner faces of said clamping plates, wedge bars adapted to coöperate with the aforesaid wedges, a vertically movable frame carrying said wedge bars, and manually operated means 45 for lifting and lowering the movable frame during the clamping and unclamping action.

6. A portable device for carrying bricks, comprising a main frame having a locomotive mechanism combined therewith, a series 50 of lifting arms rigidly supported on the lower end of said main frame, pairs of clamping plates hinged to said arms and provided on their inner faces with wedges, wedge bars adapted to coöperate with said 55 wedges, a vertically movable frame for supporting said wedge bars, together with a series of springs interposed between the frame and the wedge bars to enable the latter to have an elastic action in order to 60 compensate for inequalities in the thickness of the bricks.

7. A portable device for carrying bricks,

comprising a main frame having locomotive mechanism combined therewith, a series of lifting arms supported on the lower end 65 of said main frame, clamping members hinged to said arms, wedge bars coöperating with wedges on the clamping members, a vertically movable frame and springs interposed between it and said wedge bars so that the latter may have an elastic action, and means for lifting and lowering the movable frame, consisting of a worm gear combination. 70

8. A portable device for carrying bricks, 75 comprising a main frame having a locomotive mechanism combined therewith, a series of arms projecting from the lower end of said frame in a position at right angles thereto, a clamp arranged in connection with 80 each arm, means for moving said clamp laterally, a vertically movable frame provided with an elastic connection with said clamp-operating means, and means operated by hand for moving said latter frame up and 85 down for the purpose of actuating the clamps.

9. A portable device for carrying bricks, comprising a main frame having operating handles and wheels, a series of lifting arms 90 supported at the lower end of said frame and adapted to be inserted between the bricks of a layer, hinged clamping plates on said arms, said plates having wedges on their inner faces, wedge bars operating in 95 connection with said wedges, a vertically movable frame having a channel bar, a series of rods connected to the wedge bars and passing through perforations in the channel bar, a series of springs enveloping 100 said rods, and means for actuating the movable frame, consisting of a worm gear through which passes a screw projecting from the frame together with a worm shaft operating said gear. 105

10. A portable device for carrying bricks, comprising a main frame having handles for propelling it about and trucks or wheels on which it rolls, a series of lifting arms supported at the lower end of said main 110 frame, pairs of hinged clamping plates on said lifting arms, wedge bars coöperating with wedges on said clamping plates, and means for lifting said wedge bars, which means include individual springs for rendering the action of each wedge bar yielding to compensate for inequalities in the thickness of bricks. 115

In testimony whereof I affix my signature in presence of two witnesses.
